UNITED STATES PATENT OFFICE.

RICHARD H. CUNNINGHAM, OF NEW YORK, N. Y., ASSIGNOR TO DUBILIER CONDENSER
& RADIO CORPORATION, A CORPORATION OF DELAWARE.

ELECTRIC HEATING APPARATUS.

Application filed April 22, 1924. Serial No. 708,175.

This invention relates to improvements in electric heating apparatus, especially sad irons for smoothing and pressing cloth and garments.

- 5 An object of this invention is to provide an electrically heated iron so designed that over-heating thereof is automatically prevented, and thereby all risk of damage either to the mechanism of the iron itself, or 10 to the cloth or garment, upon which the iron is used, is obviated, preferably, the desired result is secured by a thermostatically operated circuit breaker, mounted upon the iron and working in conjunction with electrical elements to reduce the current flowing 15 through the iron, when the temperature thereof reaches a pre-determined degree.

This and other objects and advantages of the invention will appear from the following description, taken with the accompanying drawings, and the novel features of the invention are defined in the claims appended hereto; but the disclosure is illustrative only; and I may, of course, change 20 the details of structure shown herein, without departing from the essential principle of operation.

On the drawings,

Figure 1 is a view mainly diagrammatic, 30 showing a portion of an electrically heated iron, in outline, with the heating coil thereof, and the means for controlling the coil; and

Figure 2, is a side view of such an iron, 35 partly in section, indicating how the parts shown in Figure 1 may be mounted upon such an iron in practice.

The same numerals identify the same parts throughout.

40 As shown in the drawings, the iron comprises a hollow body 1 on the top of which is made fast a handle 2; and within the body 1 is the usual heating coil 3, consisting of suitable wire, through which current 45 is passed; this coil being connected to a binding post 4, which may be taken as the positive terminal; and another binding post 5, to enable the coil 3 to be conveniently connected to a supply circuit. The coil 3 50 will, of course, be inside the body 1, and the binding posts 4 and 5 are on the outside of the same. Obviously, the terminals 4 and 5 may be given any shape which will enable connection to be made in the readiest and 55 most convenient manner.

From one of the terminals, such as the terminal 4, a conductor 6 leads to a binding screw 7, which passes through a metallic bar or strip 8, supported at its opposite ends and carrying in the middle a contact 9. This 60 contact 9 ordinarily rests upon a co-operating contact 10, carried by a thermostatic member 11. This thermostatic member may be a bar of aluminum bent or bowed in the middle, and disposed adjacent the 65 bar 8, and preferably beneath the same, and from this bar leads a conductor 12, to one extremity of the coil 3, the opposite extremity being connected to the binding post 5. Ordinarily, current will 70 flow through the bar 8, the contacts 9 and 10, the member 11, and the conductor 12, to the coil 3, but if the iron should become too hot, the thermostatic member 11 75 will bend downward to a greater extent in the middle, and thus separate the contacts 9 and 10, so as to break the circuit at this point.

As shown in Figure 1, an insulated terminal 13 may be located in the line of the 80 conductor 12, for a purpose which will be described later.

The screw 7 passes through one end of the bar 8, and the adjacent end of the member 11. It makes electrical contact with the 85 bar 8, but is insulated from the member 11 by a suitable bushing 14, and a suitable washer 15; and the lower end of this screw is engaged by a nut 16, so that it can be tightened. The opposite ends of the bar 8 90 and member 11 are held together by similar parts; and the two bars, 8 and 11, are therefore electrically disconnected, so that current passing to the screw 7, connected to the conductor 6 must flow from the bar 8 95 through the contacts 9 and 10 to reach the thermostatic member. As long as the contacts 9 and 10 are together, the full current flows through the heating coil 3. Between the bar 8 and the contact 13, is a resistance 100 element 17, one end of this resistance element being attached to the contact 13, and the other being made fast under the head of one of the screws 7. This element is therefore in parallel with the contacts 9 and 10. When these contacts are together, they 105 short circuit the resistance, but in case the temperature of the iron rises to a point which has been set as the limit, the action of the member 11, separating the contacts 9 110

and 10, opens the short-circuit around the resistance element and leaves this element in circuit as the only means for connecting the binding post 4, to the coil 3. Current can now flow through the coil 3 as before, but on account of the resistance 17, it will be so reduced that the iron cannot be heated to any higher point.

The contact point 10 may be adjustably mounted in the member 11, and between this contact and the screw 7, joined to the conductor 6, I may place a condenser 18, so that this condenser will be in multiple with the contacts 9 and 10. Upon the bar 8, over the contact 9, is a cap 19, and over this cap is a mounting 20, secured by screws 21, to the iron to carry an adjusting screw 22. This screw may pass through a threaded opening in the mounting 20, and carry a binding nut 23, to engage the top of this mounting, the screw having a milled head 24, so that it can be turned to press upon the cap 19, to a greater or less extent and thus enable the contact 9 to be carried higher or forced down to a lower position, so as to regulate the action of the thermostatic circuit breaker comprising the member 11, and the two contacts 9 and 10.

When the iron is in use, current ordinarily passes through the conductors 6 and 12, to reach the coil 3, and not only does the iron become as hot as is desired, but the thermostatic circuit breaker acts to separate the contacts 9 and 10, and causes the current to flow through the resistance 17 to prevent further heating. The presence of the condenser 18 is necessary because the action of the thermostatic circuit breaker is necessarily slow, and when the contacts 9 and 10 are together, the condenser is always fully charged when the member 11 begins to move the contact 10 apart from the contact 9. Hence, if on account of the slow separation of the contacts 9 and 10, an arc should occur between these two contacts, owing to the continuance of the flow of current between these two contacts, before the resistance of the gap or space that is being made between them becomes great enough to interrupt the current entirely, the condenser will oppose the current to a sufficient extent to stop further flow of current across these two contacts, as soon as the member 11 begins to move the contact 10 away from the contact 9. Hence, any arc that might be created between these contacts, is quenched at once.

From the foregoing, it will be apparent that the iron is very effectually controlled, and that by the use of the adjusting screw

22, the limiting temperature can be varied at 60 will within permissible limits.

As indicated in Figure 2, the thermostatic member 11 with the contact 10 is disposed inside the body 1 of the iron, and the bar 8 together with the adjusting screw 22, and parts for mounting same, are on the outside of the iron; the contact 9 projecting into the body 1, through a suitable opening. The manner in which the thermostatic circuit breaker, the condenser, the resistance, and the adjusting screw 22 are assembled and disposed, with reference to the structure of the iron, is not material to the invention and the arrangement of such parts can, of course, be left to the designer, as my invention is concerned here solely with the combination described, and not the particular position which any part may occupy upon the iron carrying same. In fact, a heating iron is described above more for the purpose of explaining a specific device in connection with which my invention may be used. It can, of course, be utilized with any electrical appliance having a heating coil, the action of which is to be regulated.

Having described my invention, what I believe to be new and desire to secure and protect by Letters Patent of the United States is:—

1. The combination of a heating coil, a circuit breaker adapted to become operative when the heating of the coil has reached a pre-determined point, and a resistance connected to the coil, but normally short-circuited by the circuit breaker.

2. The combination of a heating coil, a thermostatic circuit breaker comprising a pair of contacts, a condenser in multiple with said contacts, and a resistance normally short circuited by the circuit breaker, said circuit breaker including a member becoming operative when the heating of the coil has reached a pre-determined degree, to separate the contacts and leave only the resistance in circuit with said coil.

3. The combination of a heating coil, a conducting bar, a contact carried by said bar, a cap upon said bar, a mounting adjacent said cap, an adjusting screw in said mounting, to bear upon said cap, a thermostatic member adjacent said bar and insulated therefrom, a second contact carried by said member to co-operate with the first contact, a resistance between said bar and said coil, and a condenser in multiple with said contacts, for the purpose set forth.

In testimony whereof I affix my signature.
RICHARD H. CUNNINGHAM.
